UNITED STATES PATENT OFFICE.

ARTHUR W. WADSWORTH, OF FORT THOMAS, KENTUCKY, ASSIGNOR TO THE WADSWORTH WATCH CASE COMPANY, OF DAYTON, KENTUCKY, A CORPORATION OF KENTUCKY.

WATCHCASE.

Application filed October 22, 1926. Serial No. 143,491.

This invention relates to watch cases and more specifically to strap watch cases in which I provide the strap holding lugs integrally formed with the movement ring, 5 said ring and lugs being made of base metal and entirely covered or concealed when the case is assembled with the movement and the straps.

The objects of this invention are:

10 First, to provide a watch case having the strap holding lugs formed integral with the movement ring, said ring and lugs made of base metal.

Second, to provide a movement ring having integral strap holding lugs, said ring and lugs being made of base metal and entirely concealed by precious metal when the case is assembled.

Third, to provide a watch case which 20 eliminates the space between the strap and the case which gives the case and strap a more pleasing jointure, as well as stronger construction.

Fourth, to provide a watch case having 25 a movement ring made of base metal and which is provided with integral lugs which eliminates the necessity of soldering independent lugs to said ring, as is now the practice and which prevents any danger of the 30 strap holding lugs being separated from the movement ring, as is the case with the present strap holding lugs.

Fifth, further objects of the invention are 35 to provide a strap or wrist watch case which will be stronger in construction than the present strap watch case and which can be made with a considerable saving of precious metal and one that eliminates the spaces between the straps and the watch case which 40 makes a more pleasing and harmonious connection between the strap and the case.

This invention consists in a watch case movement ring made of base metal and provided with integral strap holding lugs, said 45 lugs and ring being covered up or concealed by the back and bezel which are of precious metal and which snap onto said movement ring.

The invention further consists in the construction, combination, location and arrangement of parts, as herein set forth and claimed.

In the drawings:

Fig. 1 is a plan view of the entire watch

case showing the bezel covering the strap 55 holding lugs;

Fig. 2 is an enlarged side elevation thereof showing half in vertical section;

Fig. 3 is an end elevation of the watch case half shown in vertical section;

Fig. 4 is an inside plan view of the back;

Fig. 5 is a longitudinal vertical section of the bezel;

Fig. 6 is a perspective view of the invention 65 with the crystal and movement removed, parts being broken away to show the manner of attachment between the movement ring, back and bezel;

Fig. 7 is a perspective view of the entire 70 watch and showing a portion of the watch straps; and

Fig. 8 is an isometric view of the watch case movement ring.

In the embodiment of my invention as 75 illustrated and which shows a preferred construction, I provide a strap watch case comprising bezel 1, crystal 2, movement ring 3 and back 4. Referring to movement ring 3, this part is made of base or non-precious 80 metal while the bezel 1 and back 4 are made of precious metal, such as gold, silver, platinum, etc. 5 represents the watch strap holding lugs which are integral with movement ring 3 and, therefore, of base or non-precious metal. Heretofore said lugs 5 were made 85 separate from movement ring 3 and extended outside or beyond bezel 1 and back 4 and for this reason were made or plated with gold or like precious metal. Holes 6 centrally located in the ends of lugs 5 receive the usual 90 sliding pins 7 of strap bars 8, said strap bars containing the usual spring (not shown) for forcing the pins outwardly into engagement with hole 6. It will be observed that when 95 the parts are assembled with the back 1 and bezel 4 mounted over movement ring 3 in engagement with each other that the outer sides of hole 6 will be concealed by the bezel 1, as shown in Figs. 6 and 7, and that the inner sides of said holes, as well as of the 100 lugs 5, will be covered and concealed by the looped ends 10, as shown in Fig. 7. Movement ring 3 is substantially rectangular in form and practically the shape shown in the drawings. The ends of said ring 3 are concaved or hollowed out at 9 to provide clearance between said ring 3 and strap bars 8 for looped ends 10 of straps 11 in order to per-

mit said strap loops to entirely cover and conceal the non-precious metal of movement ring 3 and lugs 5. Annular shoulder 12 located in the bottom 13 of movement ring 3 is slightly undercut or tapered inwardly and is adapted to frictionally receive annular recessed flange 14 cut in back 4 and which is correspondingly undercut so that back 4 can be easily snapped onto movement ring 3 and 10 tightly held thereon. The ends 15 and 16, respectively, of back 4 have integrally extended portions 17 which are provided with recesses 18 to accommodate lugs 5 of movement-ring 3 and are also provided with upper turned walls 18^a, as clearly shown in Fig. 2. Bezel 1 is provided with bezel opening 19 and crystal groove 20 which are centrally located in the top thereof. The ends 21 and 22, respectively, of bezel 1 are cut away to 20 form openings 23, which openings receive the looped ends 10 of strap 11. Crystal 2 is fitted within crystal groove 20 in bezel 1. The inner surface 25 of wall 25^a of bezel 1 is slightly larger than the outer periphery 26 of movement ring 3 so that said bezel is adapted to snugly fit over said ring, the lower edge 25^b of said bezel resting on the outer edge 27 of back 4 when in assembled position, as clearly shown in Figs. 2, 3, 6 and 7.

Referring to Fig. 2, ends 21 and 22, respectively, of bezel 1 are provided with slightly enlarged portions 28 which snap into engagement with edge 29 of movement ring 3 whereby said bezel is securely held in fixed relation with said movement ring 3 and back 4. The movement (not shown) is held within central opening 30 in ring 3 by the usual and well-known methods.

To assemble the watch case, we will assume that the movement has been mounted in opening 30 of movement ring 3.

The next step is to snap back 4 onto movement ring 3.

Then, after the crystal 2 has been mounted in bezel 1, said bezel is received over movement ring 3 until enlarged portions 28 of said bezel engage edge 29 of said ring and the lower edge 25^b of said bezel rests on outer edge 27 of back 4, as clearly shown in Figs. 2 and 6.

Then place pin bars 8 within looped ends 10 of straps 11 and insert sliding pin 7 within hole 6 in lugs 5.

Heretofore it has been the practice to solder, braze or otherwise permanently fasten lugs 5 to movement ring or center 3. This is not only slow and tedious hand work but is also expensive as well. With my improved center 3 having the lugs 5 integral therewith, the expensive operation of soldering is eliminated. The lugs 5 being integral

with movement ring 3 also produces a watch case of stronger construction.

An advantage of this invention is that the movement ring 3 and lugs 5 can be made of base metal, which is much more economical to use than precious metal, and that bezel 1 and back 4, when snapped onto said movement-ring 3 entirely covers or conceals said movement ring 3 and lugs 5. This construction further beautifies a strap watch case, inasmuch as it eliminates the usual space between the strap and the watch case and thereby gives a more harmonious jointure between the straps and the watch case.

It will be understood that my invention is capable of certain changes and modifications without departing from its scope or spirit as defined in the claims.

What I claim as new and desire to secure by Letters Patent is:

1. In a watch case construction, the combination of a movement ring having spaced apart holding lugs, a back and bezel each adapted to be removably mounted upon said movement ring and holding lugs, and a strap bar attached to said lugs, whereby when a strap is mounted on said bar between said lugs, said back, bezel and strap entirely conceal said movement ring and holding lugs.

2. In a watch case construction, the combination of a movement ring having spaced apart holding lugs, the end of said movement ring being concaved or hollowed out between said lugs, a back and bezel adapted to be removably mounted upon said movement ring and holding lugs and in engagement with each other, and a strap bar attached to said lugs, whereby when a strap having a loop is mounted on said bar between said lugs and within said hollowed out space said strap covers and conceals the inner exposed sides of said holding lugs and whereby said center and holding lugs are completely concealed by said back, bezel and strap.

3. In a watch case construction, the combination of a movement ring having spaced apart holding lugs, the end of said movement ring being concaved or hollowed out between said lugs, a back and bezel adapted to be mounted upon said movement ring and holding lugs and in engagement with each other, and a strap bar attached to said lugs whereby when a strap having a loop is mounted on said bar, between said lugs and within said hollowed out space, said strap covers and conceals the inner exposed sides of said holding lugs and whereby said center and holding lugs are substantially concealed by said back, bezel and strap.

ARTHUR W. WADSWORTH.
